UNITED STATES PATENT OFFICE.

ERNEST C. SCHRADE, OF KNOXVILLE, PENNSYLVANIA.

GLASS-PRESS.

No. 843,849.

Specification of Letters Patent.

Patented Feb. 12, 1907.

Application filed December 22, 1905. Serial No. 292,948.

To all whom it may concern:

Be it known that I, ERNEST C. SCHRADE, residing at Knoxville, in the county of Allegheny and State of Pennsylvania, a citizen of the United States, have invented or discovered a certain new and useful Improvement in Glass-Presses, of which improvement the following is a specification.

The invention described herein relates to certain improvements in glass-presses, and has for its object a construction of mechanism wherein with a constantly-operating power the table for presenting the molds to the press and the press-mechanism power are operated intermittently and the movements of the table and press mechanism are controlled each by the other.

The invention is hereinafter more fully described and claimed.

In the accompanying drawings, forming a part of this specification, Figure 1 is a front elevation of my improved press. Fig. 2 is a side elevation of the same. Fig. 3 is a sectional elevation on a plane indicated by the line III III, Fig. 1. Figs. 4 and 5 are sectional plan views on planes indicated by the lines, respectively, IV IV and V V, Fig. 1. Fig. 6 is a sectional view on a plane indicated by the line VI VI, Fig. 4. Figs. 7 and 8 are sectional detail views.

In the practice of my invention the mechanism is preferably mounted upon a platform 1, having wheels or rollers 2, whereby it may be readily shifted from place to place as required. The power-shaft 3, which can be driven by any suitable motor—as, for example, an electric motor, as indicated at 4—is mounted in suitable bearings secured to the bed-plate 1. The table 5, carrying the molds 6, is loosely mounted upon a vertical spindle 7, the connection between the table and the driving power being preferably frictional and of such character as will insure the rotation of the table when unlocked, as hereinafter described. The table is driven from the power-shaft through a suitable interposed mechanism or gearing, which when employing a high-speed power as an electric motor is preferably formed by worms and gears 8 and 9 when the power-shaft is so located as to require a counter-shaft 10. It is preferred that a driving-head 7^a should be connected to the worm-wheel of gearing 9 and that a disk 7^b of suitable material should be interposed between the head and table, so as to insure the rotation of the latter when un-

locked. The pressing mechanism is operated by a shaft 11, which is also driven from the power-shaft 3, through suitable interposed gearing, which can be connected to 60 and automatically disconnected from the shaft, as hereinafter described. In the construction shown the shaft 11 is driven from the shaft 10 through suitable interposed gearing consisting of the gear-wheels 12, 13, 65 and 14, the gear-wheel 14 being loosely mounted upon a shaft 15 and being provided with a member 16 of a clutch mechanism, the other member 17 being so connected to the shaft 15 as to be capable of being shifted 70 along the shaft and to drive the same when placed in engagement with the member 16. The shaft 15 has a pinion 18 secured thereon and intermeshing with a gear 19 on the shaft 11. The movable member 17 of the clutch 75 is provided with a peripheral groove for engagement with the arms of a yoke 20, secured to a sliding rod 21, which is provided with an arm 22, projecting out parallel with the side of the gear-wheel 19. This gear-wheel 19 is provided with a projection or dog 23, which during the rotation of the gear-wheel 19 will strike against the arm 22 and shift the rod 21 longitudinally in such direction as to effect a disengagement of the clutch 80 member 17 from the member 16, thereby stopping the operation of the pressing mechanism. The rod 21 is held in a direction opposite that in which it is moved by the projection 23 by a spring 26, surrounding the 90 rod, as clearly shown in Figs. 5 and 6.

As in the operation of the machine it is desired that the table should be operated to carry a new mold into position under the pressing-plunger, as soon as the pressing 95 mechanism has ceased operation, provision is made for unlocking the table simultaneous with the disengagement of the pressing mechanism from its driving means. In the construction shown the table-lock consists of a 100 pin 27, movably mounted in the frame of the machine and adapted to be forced up to engage holes 28 in the table 5 when a mold is in proper position under the pressing-plunger. This pin can be operated from the rod 21 in 105 any suitable manner—as, for example, by means of a bell-crank lever 28, connected to a collar or lug 29, secured to the rod 21. By this construction the longitudinal movement of the rod 21, which opens the clutch mechanism, will at the same time withdraw the pin 110 27 from engagement with the table, thus per-

mitting the latter to be rotated by frictional engagement with its driving-shaft.

While the operation of the parts for connecting the pressing mechanism with its driving means and for unlocking the table can be made automatic, both as regards the disengagement of the driving mechanism from the pressing mechanism and unlocking of the table and also of the locking of the table and the connection of the driving mechanism with the pressing mechanism, it is preferred that the latter operations—*i.e.*, the locking of the table and the connection of the driving mechanism with the pressing mechanism—should be controlled by the operator. Hence provision is made for shifting the rod 21 longitudinally by means of a treadle 30, connected to a shaft 31, to which is secured an arm 32, engaging the rod 21.

20 The projection 23 is preferably made in the form of a dog, pivotally mounted in a recess in the gear-wheel 19 and normally or just prior to its engagement with the arm 22 lies partially within the recess in the gear-wheel. 25 As the gear-wheel in its rotation in the direction of the arrow *a* in Fig. 8 brings the dog 23 into engagement with the arm 22, the dog will turn on its pivot-pin and move outward, pushing the arm 22 to the left, and thereby 30 shifting the rod 21, as hereinbefore described, to disengage the members of the clutch. When it is desired that the pressing mechanism should again operate, the operator depresses the treadle 30, thereby moving the rod 21 to 35 the left in Figs. 5 and 6. This movement of the rod 21 will shift the arm 22 out of contact with the dog 23, permitting it to drop back into its recess, so that on the removal of the foot of the operator from the pedal the spring 40 will move the rod 21 to the right, causing 45 the clutch members to engage and forcing the pin 27 into engagement with the table.

The pressing mechanism consists of a cross-head 33, movably mounted on guide-rods 34, secured to the frame of the machine. The outer ends of this cross-head are provided with trunnions for the reception of the heads on the rods 35, which extend down and are connected, as shown in Fig. 2, to arms 36, secured to a rocking shaft 37, mounted in suitable bearings on the frame of the machine. These arms are provided with curved grooves or slots 38 for the reception of pins 39, eccentrically mounted on disks 40, secured to the shaft 11. The grooves or slots are so shaped that when the pin is passing along the portion *b* thereof there will be a dwell of the plunger in its lowest position, thereby affording an opportunity for the glass to set and harden 55 after being forced to the desired shape of the mold. While not necessary, it is preferred to counterbalance the weight of the cross-head and other parts carried thereby by means of a weight 41, adjustably secured on an arm 42 60 on the shaft 37.

The mold-ring is secured to a plate 43, which is carried by a plate 44, provided with guiding-sleeves surrounding the rods 34. This mold-ring has the usual or any suitable resilient connection to the carrying-plate 44.

70 In hand-operated presses the operator can tell by the feel the amount of pressure required to properly shape an article and when the mold is filled. In power-machines provision should be made so that only a certain predetermined pressure can be exerted upon the glass. To this end I provide means interposed between the cross-head 33 and the rod 45, carrying the plate 44 and the plunger 46, whereby only a certain predetermined 75 pressure can be applied to the glass in the mold. As shown, a block 47 is adjustably supported on the rod 45 by means of a nut 48, screwing on the threaded portion of the rod. This block 47 is provided with fulcra 49 for 80 the levers 50, said levers being by preference connected by the fulcra by pins 51. The inner ends of these levers 50 are loosely connected, preferably by links 52, to the cross-head 33, preferably through a disk 53, provided with lugs 54, to which the links 52 are also connected. This disk 53 is provided with a stem 55, secured to the cross-head 33. Weights 56 are movably mounted upon the levers, it being preferred that antifriction- 85 bearings, such as the rollers 57, should be interposed between the weights and the levers, so that the weights will move freely and quickly along the same. The movements of the weights on the levers are limited by adjustable stops 58 and 59.

90 It will be readily understood by those skilled in the art that when a certain predetermined resistance is presented to the plunger 46, such resistance being fixed by 95 the position of the weights 56 on the levers, that the inner ends of the levers will be depressed, raising their outer portions so that the weights will move inwardly, so that thereafter a less pressure will be exerted on the 100 glass proportional to the inward movement or extended inward movement of the weights along the levers.

In order to prevent a shock to the machinery, due to the return movement of the 105 weights 56 and the dropping of the levers 50, when the cross-head begins its upward movement it is preferred to employ dash-pots to regulate these return movements. As shown 110 in Fig. 3, these dash-pots consist of cylinders 115 60, in which move pistons 61, connected by stems to the levers. A valve is so arranged 120 as to permit the ready upward movement of the outer ends of the ends of the levers, but will control and steady the return movements 125 thereof.

130 In order to provide for the removal of the articles from the molds 6, movable bottoms 63 are provided, said bottoms resting upon pins 64, extending down through the

table 5. A circular track 65 extends for a distance along the path of movement of these pins for a portion of their circular traverse and is so arranged as to effect an upward movement of the pins 64. It at times happens that the glass has not hardened when the ejectors operate thereon, with the result that the bottom of the glass is forced upward without forcing the upper portions of the articles above the mold. In order under such conditions to insure the removal of the glass, the track 65 is pivotally connected at one end to a suitable support, while other portions are supported by suitable means, one of which is made movable, so that the track can be raised when desired. In the construction shown this movable support consists of a sleeve 66, surrounding a post 67, secured to the frame of the machine and connected by a link to an operating-lever 68. By depressing this lever and sleeve 66 and with it the track 65 can be raised, thereby further forcing up any pins 64 resting thereon.

25 While not necessary, it is preferred to employ suitable means for preventing any movement of the pressing mechanism due to momentum after the shaft 11 has been disconnected from its driving mechanism. A suitable form of such stop mechanism consists of spring-actuated pins 69, arranged to engage a notch in the periphery of the disks 40, as shown in Fig. 7.

When the table is operated at a considerable speed, it is possible that at times the holes in the table will be carried past the pins 27, or if not carried past there will be an undesirable shock or jar, due to the engagement of the pins with the table. In order to prevent either of these contingencies, a brake is employed to check the movement of the table as one of the holes therein comes into alignment with the pin 27. In the construction shown this brake consists of a spring-actuated arm 70, adapted to engage the bosses 71 on the under side of the table, through which the passages for the pins 64 are formed, as shown in Figs. 1, 2, and 4.

In describing the operation of this machine 50 it will be supposed that the pressing mechanism is at the upper limit of its movement and the table has been so shifted as to bring a mold into operative relation with the plunger 46. The operator depresses the treadle 30, thereby shifting the rod 21 to the left to release the dog 23, which will drop, as before stated, into the recess in the wheel 19. When the treadle is released, the spring 26 will force the rod 21 to the right, causing the clutch members to engage and also forcing the pin 27 up to lock the table in position. Thereafter the driving-head 7^a will rotate without affecting the table, and the gear-wheel 19 will be driven to operate the disks 65 40, causing the pins 39 to shift the levers 36

and pull down the plunger. When the shaft 11 has made one rotation, thereby drawing down the plunger and returning it to normal upper position, the dog 23 will engage the arm 22, shift the rod 21 to the right, separating the clutch members, and withdrawing the pin 27 from the table, which will thereafter be rotated until another mold comes into proper position with reference to the plunger. The operator can depress the lever 70 immediately after the table begins to rotate, thereby releasing the dog 23, as this release will not permit a return of the rod 21 to the right, it being held in its position to the left as soon as the table begins to rotate by the pin 27 bearing on the under side of the table. When the treadle is depressed, as it should be immediately after the table begins to rotate, stoppage of the table will be automatic.

I claim herein as my invention— 85

1. In a pressing mechanism, the combination of a pressing mechanism, a mold-table, a continuously-operating power-shaft, continuously in driving relation to the table, and means operative by the shaft for alternately 90 nullifying the function due to such relation and connecting the pressing mechanism to the shaft.

2. In a pressing mechanism, the combination of a continuously-operating power-shaft, 95 a table having a frictional driving connection with said shaft, a pressing mechanism and means controlled by the pressing mechanism for locking the table.

3. In a pressing mechanism, the combination of a continuously-operating power-shaft, 100 a table having a frictional driving connection with said shaft, a pressing mechanism, a table-lock, means for connecting the pressing mechanism to the power-shaft, said lock and 105 connecting means being controlled by the pressing mechanism.

4. In a pressing mechanism, the combination of a continuously-operating power-shaft, 110 a table having a frictional driving connection with said shaft, a pressing mechanism, and means controlled by the table for connecting the pressing mechanism with the power-shaft.

5. In a pressing mechanism, the combination of a plunger, a cross-head, means for operating the cross-head and a yielding connection between the cross-head and plunger whereby the pressure exerted by the plunger may vary automatically in proportion to the resistance to the plunger. 115

6. In a pressing mechanism the combination of a plunger, a cross-head, means for operating the cross-head and an adjustable and varying yielding connection between the cross-head and plunger, whereby the pressure exerted by the cross-head may vary automatically in proportion to the resistance to the plunger. 125

7. In a pressing mechanism, the combination of a plunger, a cross-head, means for op- 130

- erating the cross-head, a connection from the cross-head to the plunger presenting a gradually-decreasing resistance to the movement of the cross-head independent of the plunger.
- 5 8. In a pressing mechanism, the combination of a plunger, levers pivotally connected to the plunger, weights movably mounted on the levers, and a cross-head operative on the levers to shift the plunger.
- 10 9. In a pressing mechanism, the combination of a mold-table, means for rotating the table, ejectors for forcing articles from the molds, a track for shifting the ejectors and means for shifting the track.
- 15 10. In a pressing mechanism, the combination of a continuously-operating power-shaft, a mold-table having a frictional driving connection to said shaft, a pressing mechanism and means for intermittently connecting the pressing mechanism to the power-shaft. 20
11. In a pressing mechanism, the combination of a continuously-operating power-shaft, a mold-table having a frictional driving connection to said shaft, means for arresting the movement of the table, a pressing mechanism, a clutch mechanism for connecting the pressing mechanism to the power-shaft, and means operative by the pressing mechanism to open the clutch and to shift the table-arresting means. 25
- 30 In testimony whereof I have hereunto set my hand.

ERNEST C. SCHRADER.
